LIFT FOR HEAVY OBJECTS

Howard H. Vermette, 7 E. 143rd St.,
Hammond, Ind. 46320

Filed Dec. 1, 1965, Ser. No. 7

Term of patent 14 years

(Cl. D41—1)

FIG. 1 is a front perspective view of my lift for heavy objects with arms in a raised position;

FIG. 2 is a rear perspective view with arms in the lowered position, and

FIG. 3 is a perspective view on an enlarged scale disclosing operating means shown in FIG. 1.

The dominant features reside in the solid line portion.

I claim:

The ornamental design for a lift for heavy objects, as shown and described.
